PRODUCTION OF WOOD PRESERVATIVES

Jacquelin E. Harvey, Jr., Atlanta, Ga., assignor
of one-half to Southern Wood Preserving Com-
pany, East Point, Ga., a corporation of Georgia

Application August 14, 1940, Serial No. 352,663

2 Claims. (Cl. 196—53)

The present invention relates to the production of wood preservatives.

More specifically, the present invention relates to the production of wood preservatives of lowered corrosivity from tars of aromatic content and fractions thereof.

An object of the present invention is the induction of toxicity in hydrocarbons having little or no toxicity, and of increasing toxicity in hydrocarbons having toxicity, whereby to provide, among other things, wood preserving oils of lowered corrosivity, or materials having induced toxicity and lowered corrosivity adapted to be added to the wood preserving oils or the like.

An object of the present invention is the improving of toxic value in wood preserving oils of current manufacture; the improving of toxic properties in the parent materials of wood preserving distillates of current manufacture; and the improving of toxic properties in residual materials resulting from a distillation recovery of wood preserving oils from tars or the like; the improving of toxic properties being attended by lowering of corrosivity.

Other objects of the present invention will be apparent from the following disclosures.

The invention will be understood from the following description of illustrative steps comprising various methods of securing the objects of the invention, when read in connection with the accompanying drawing wherein the figure is a diagrammatic sketch of an apparatus for carrying out a form of the process of the invention and wherein the nature of the step carried out in each chamber and the contents thereof are indicated by legend.

Example 1.—A sulphur bearing coal tar creosote of known toxic value and having a specific gravity of substantially 1.08, a coke residue of in the order of 2% and substantially 35% residue above 355° C. is treated with hydrogen at a temperature of 350° C. and a pressure of 300 atmospheres; the thus treated coal tar creosote will be found upon inspection to have reduced corrosivity which advantage will pass to the finally processed material. The coal tar creosote of reduced sulphur content is passed through a high pressure reaction chamber while simultaneously flowing hydrogen therewith, at a temperature of 400° C. and a pressure of 200 atmospheres. The catalyst is molybdenum oxide, flow of hydrogen 11,000 cubic feet per barrel creosote and the time of reaction 45 minutes. The beneficiated creosote flowing from the reactor is inspected and found to have increased toxic properties as stemming from among other things reduced coke residue, specific gravity, and viscosity; it will be found that there has been induced no substantial percentage of liquid chain structures or kindred materials that precluded the induction of toxicity.

If an unwanted percentage of low boiling fractions exist, they may be stripped to make the newly formed oil of induced toxicity and lowered corrosivity conform in its low boiling end to a wood preserving oil of trade acceptance.

Example 2.—A sulphur bearing coal tar, specific gravity 1.1641 and coke residue of substantially above 10% is treated with hydrogen at a temperature of 325° C. and a pressure of 200 atmospheres; the thus treated coal tar will be found upon inspection to have reduced corrosivity which reduction will be reflected in the finally processed material. The coal tar of reduced sulphur content is passed through a high pressure reaction chamber while simultaneously flowing hydrogen therewith at a temperature of 395° C. and a pressure of 250 atmospheres while contacting a vanadium oxide catalyst. The flow of hydrogen is 12,000 cubic feet per barrel feed stock and time of reaction one hour.

The beneficiated coal tar flowing from the reactor is inspected and found to have increased toxic value as stemming from among other things reduced coke residue, specific gravity, and viscosity, and the fact that no substantial percentage of liquid chain structures or kindred materials has been induced to lower toxicity, or make the induced toxicity of the present invention impossible.

In the event any percentage of undesirable low boiling fractions exist in the beneficiated tar, said undesirable low boiling fractions may be stripped to provide conformance in the low boiling end to wood preservatives of trade acceptance. Thus, by the process of the present invention there is provided a wood preserving oil of induced toxicity and lowered corrosivity that conforms in its low boiling end to a wood preserving oil of trade acceptance.

Example 3.—A sulphur bearing coal tar fraction whose initial boiling point is substantially 240° C. and characterized by content of high molecular complexes is treated with hydrogen at a pressure of 200 atmospheres and 340° C.; the thus treated coal tar fraction will be found upon inspection to have reduced corrosivity which fact will inure to the finally processed material. The coal tar fraction of reduced sulphur content is subjected to the action of a flow of hydrogen in the presence of a molybdenum oxide catalyst while passing said tar fraction through a high pressure reaction chamber at a temperature of 400° C. and a pressure of 310 atmospheres. The flow of hydrogen is 15,000 cubic feet per barrel feed stock and the reaction period, 75 minutes.

The beneficiated coal tar fraction flowing from a reactor is inspected and found to have increased toxic value as stemming from among other things reduced coke residue, specific gravity, and vis-

cosity and the fact that no substantial percentage of liquid chain structures or kindred materials had been induced to lower toxicity, or to make the induced toxicity of the present invention impossible.

In the event any percentage of undesirable low boiling fractions exist in the beneficiated tar, said undesirable low boiling fractions may be stripped to provide conformance in the low boiling ends to wood preservatives of trade acceptance. Thus, by the process of the present invention there is provided a wood preserving oil of induced toxicity and lowered corrosivity that conforms in its low boiling end to a wood preservative of trade acceptance.

If desired the beneficiated tar or fraction thereof may be distilled for the recovery of a wood preserving distillate of enhanced toxic value; the distillation recovery may be effected to an upper limit so that the distillate will conform in its low boiling end to a wood preserving oil of trade acceptance; or, the distillation may be effected to any desired upper limit with the removal of, if necessary, low boiling fractions in said distillate to provide specification conformance.

In accordance with process of the present invention, wood preserving oils of varied characteristics may be made as for instance forming substitutes for any of the wood preserving oils noted in the following:

WOOD PRESERVING IMPREGNANTS

Specification

1. A. W. P. A.:
  - a. Up to 210° C., not more than 5%
  - b. Up to 235° C., not more than 25%
2. A. W. P. A.:
  - a. Up to 210° C., not more than 1%
  - b. Up to 235° C., not more than 10%
  - c. Up to 355° C., not more than 65%
3. A. W. P. A.:
  - a. Up to 235° C., not more than 1½%
  - b. Up to 300° C., not more than 16½%
  - c. Up to 355° C., not more than 45%
4. A. W. P. A.:
  - a. Up to 210° C., not more than 8%
  - b. Up to 235° C., not more than 35%
5. A. W. P. A.:
  - a. Up to 210° C., not more than 10%
  - b. Up to 235° C., not more than 40%
6. A. W. P. A.:
  - a. Up to 210° C., not more than 5%
  - b. Up to 235° C., not more than 15%
7. Prussian Ry.:
  - a. Up to 150° C., not more than 3%
  - b. Up to 200° C., not more than 10%
  - c. Up to 235° C., not more than 25%
8. N. P. V. & L. A. #220
  - a. 5% at 162° C.
  - b. 97% at 270° C.
9. S. P. S. S. O.:
  - a. 5% at 137° C.
  - b. 95% at 257° C.
10. N. S. S. O.:
  - a. I. B. P., 150° C.
  - b. 5% at 205° C.
  - c. 95% at 292° C.

The abbreviations are explained as follows: A. W. P. A., American Wood Preservers Association; N. P. V. & L. A., National Paint, Varnish & Lacquer Association; S. P. S. S. O., Southern Pine Shingle Stain Oil; and N. S. S. O., Neville Shingle Stain Oil.

Catalysts of the present invention are oxides, as for instance oxides of metals of the 6th and 8th periodic groups; the oxides of other groups are usable, however, difficultly reducible oxides 5 are preferred.

Concerning the reaction conditions in the step that lowers corrosivity by the action of hydrogen, temperatures and pressures may be chosen within a wide range inasmuch as sulphur reduction 10 occurs at lowered temperatures and pressures. The lower limit of temperature and pressure is advisably that temperature and pressure which effects said reduction in a commercial manner, as regards the time element; pressures as high as 15 practicable will operate, and the upper limit of temperature advisable is that temperature which causes under the conditions of the process no substantial deposition of carbon, as for instance coking.

20 The step characterized by reduction of corrosivity may be carried on in a high pressure bomb or in a continuous manner in a reaction chamber or several reaction chambers, and in event of the continuous practice, the hydrogen 25 flow is preferably maintained so as to induce no substantial carbon deposit; as for instance coking. In the second cycle of hydrogen action, flows of hydrogen in the order of 8,000-15,000 cubic feet per barrel feed have proven satisfactory, however, higher or lower flows may be used, the high and low limits thereof being defined as those flows that induce undesirable coking.

By the term beneficiated as used herein and 35 in the appended claims is meant the starting material at least once subjected to the action of hydrogen in accordance with the present process.

Starting materials consist of tars of aromatic content and fractions thereof characterized by 40 sulphur content and capable of having toxicity induced therein.

The present invention is predicated on, among other things, controlling hydrogen action in both 45 cycles so that no substantial percentage of liquid chain structures or kindred materials are induced that would preclude or lower aforesaid toxicity induction. Hydrogen action is also controlled so that no substantial percentage of the starting material is converted to coke.

50 The second cycle of hydrogen action may be practiced at lowered pressures and temperatures; however, pressures of in the order of 200-400 atmospheres are preferred, but higher or lower pressures may be used. Temperatures in excess of 300° C. are preferred; however, lower temperatures may be used, the upper limit of usable temperatures being defined by those temperatures that cause no inordinate coking action.

Some of the starting materials in which toxicity 60 may be induced in accordance with the present invention may contain high molecular complexes that are especially susceptible to thermal degradation; these materials may have toxicity induced therein while higher pressures obtain 65 with the added benefit that said molecular complexes are reduced to a greater extent, thereby enhancing toxicity induction.

The time element of the present invention in the second cycle of hydrogen action is not circumscribed by any definite limit, but is merely that period necessary to show toxicity induction; using some starting feeds, periods of 30 minutes or less will result in the enhanced toxicity. Periods of one hour or longer may be used.

75 In the first cycle of hydrogen action that re-

duces sulphur content, the reduction of sulphur may be accomplished in the presence of a catalyst. Catalysts effective in the presence of hydrogen are usable, as for instance the oxides and/or sulfides of molybdenum, vanadium, uranium, cobalt, tin, manganese, tungsten, or the like.

Starting materials previously subjected to the action of hydrogen are suitable starting materials.

In the disclosures herein made the removing of low boiling fractions by gas movement or pressure release is considered the equivalent of distillation.

When reference is made to high molecular complexes contained in the starting material, and when the starting material contains low boiling fractions that are not considered high molecular complexes, it is of course obvious that the high molecular complexes contained in the starting material are to a certain extent depolymerized by the solvent present.

Starting materials of the present process also include sulphur bearing tars of aromatic content from which low boiling fractions have been removed, as for instance tars from which solvent oils have been removed. Viewed broadly, the starting materials of the present process are sulphur bearing tars of aromatic content, fractions of said tar more viscous than the starting material due to removal of low boiling fractions from the starting material, high boiling fractions and pitches.

It will be seen that by reduction of sulphur content of the material under treatment during any stage of hydrogen action, the oxide catalyst used during subsequent stages is at least partially protected from the effect of the sulphur.

The term pitch as used herein includes the higher boiling fractions of tar, in other words, tar from which low boiling ends have been

stripped, such low boiling ends being suitable for use per se as creosote, other wood preservative, or solvent. For instance, the final residue resulting from evaporating tar to dryness and then stripping wood preservative from the distillate is a very suitable pitch for use as a starting material of the present process.

Minor changes may be made within the scope of the appended claims without departing from the spirit of the invention.

I claim:

1. In the production of an oil of induced toxicity the process which comprises: subjecting a sulfur-bearing mixture of high temperature coal tar fractions to the sulfur reducing effect of hydrogen; thereafter subjecting said sulfur-refined material to the action of a flow of hydrogen in the presence of an oxide catalyst at a temperature and pressure of at least about 300° C. and 200 atmospheres, respectively; carrying on the process for such a length of time as to provide an oil of the wood preserving type having induced toxicity conforming in boiling points according to specifications accepted in the trade 25 for a tar-derived wood preserving impregnant.

2. In the production of an oil of induced toxicity the process which comprises: subjecting a sulfur-bearing mixture of high temperature coal tar fractions to the sulfur reducing effect of a flow of hydrogen at a temperature not substantially less than 325° C.; thereafter subjecting said sulfur-refined material to the action of a flow of hydrogen in the presence of an oxide catalyst with time, temperature and pressure so controlled as to provide an oil of the wood preserving type having induced toxicity and conforming in boiling points according to specifications accepted in the trade for a tar-derived wood preserving impregnant.

JACQUELIN E. HARVEY, JR.
